DESK LIGHTER

John C. Wistrand, St. Paul, Minn., assignor to Brown & Bigelow, St. Paul, Minn.

Application June 20, 1956, Serial No. 41,990

Term of patent 14 years

(Cl. D48—27)

FIG. 1

FIG. 2

FIG. 3

FIG. 4

I claim:

The ornamental design for a desk lighter, as shown.
